VOLTAGE REFERENCE TUBE

Gerald G. Carne, Rockaway, N. J., assignor to
 Radio Corporation of America, a corporation
 of Delaware

Application May 15, 1947, Serial No. 748,270

6 Claims. (Cl. 250—27.5)

1

My invention relates to a gaseous discharge device and more particularly to an improvement in a voltage reference tube.

Since the voltage drop across a cold cathode-glow discharge tube is substantially independent of the current through the tube over a wide range of current values, tubes of this type are used in voltage regulator circuits in applications where it is necessary to maintain a constant D.-C. output voltage across a load, independent of load currents and moderate line-voltage variations. Such a regulated power supply finds application with laboratory test equipment, as a substitute for batteries, or to provide a constant source of voltages for plate, screen or grid bias of vacuum tubes.

One of the most serious drawbacks to the use of known glow discharge tubes in D.-C. voltage regulator circuits for some applications, is the abrupt changes or jumps in the voltage of the tube in the order of tenths of volts. These jumps in voltage are observed to be a result of the "cathode glow" shifting from one section of the cathode area to another.

Another type of instability during the operation of certain kinds of tubes of the glow discharge type, takes the form of a slowly increasing voltage during the operational life of the tube. The voltage of such tubes has been known to increase an amount of 5 volts in 200 hours of tube operation. This voltage change requires constant adjustment whenever measurements are to be made. Such a voltage change has proved detrimental in some voltage regulator systems. This slow shift of tube voltage is due to a slowly changing cathode work function.

It is therefore an object of my invention to provide a glow discharge tube of improved operation.

It is also an object of my invention to provide an improved glow discharge tube in which the abrupt changes in tube voltage are eliminated.

It is also an object of my invention to provide a glow discharge tube having a constant voltage characteristic during the operational life of the tube.

The novel features which I believe to be characteristic of my invention are set forth with particularity in the appended claims, but the invention itself will best be understood by reference to the following description taken in connection with the accompanying drawing, in which:

Fig. 1 is an elevational sectional view of a gas discharge tube according to my invention; and

Fig. 2 is a graph showing the relationship between changes in voltage and changes in current of my improved tube.

2

The tube of Fig. 1 is a glow type discharge tube having an evacuated envelope 10. Within the envelope 10 there is enclosed a gaseous medium comprising principally of a mixture of neon and argon. The envelope 10 has a tubular configuration in which the upper end is closed by sealing off at 11 after exhaust and filling with gas. The lower end of the tubular envelope is closed by having a glass button stem 12 sealed at its periphery to the tubular envelope 10. Sealed through the bottom of the glass stem base 12 are a plurality of metal base pins 18 which extend into the envelope and form electrical leads to the several electrodes enclosed therein. Supported from the stem base 12 of the tube is an annular cathode plate electrode 14 having an open apertured center portion 15. The cathode plate 14 is supported by metal rods 16 sealed through the glass stem 12 as extensions of respective base pins 18. Support rods 16 are fixed to the under side of the cathode plate. Also, supported from the button stem 12 is an anode rod electrode 20 extending coaxially within the tube envelope 10 and through the center of the cathode opening 15. The anode rod 20 is spaced from the cathode plate 14. The lower end of the anode rod 20 is supported below the cathode plate 14 by a transverse metal support 24 which in turn is mounted on the button stem 12 by support rods 26. Rods 26 may also be extensions of respective base pins 18 sealed through the glass stem 12. The upper end of the anode rod 20 is maintained in alignment coaxial within the tube envelope 10 by a spacer mica 28. A rivet-sleeve 30 is welded to the top of the anode rod 20 and fastened by metal fasteners 31 to the mica spacer 28. The mica spacer 28 also supports a getter support wire 32 formed as a horse shoe loop. Between the ends of the wire loop 32 a channel member 33 is fixed. This channel member contains the getter material, which is flashed during manufacture, as is well known in the art. Mounting the getter support loop 32 on the mica is a metal tab 34, mechanically locked through the mica. The operation of the tube is such that, when appropriate voltage drop is established across the cathode electrode 14 and the anode rod 20, a glow discharge will occur. By providing appropriate metal for the emitting cathode surface of electrode 14 and an appropriate mixture of rare gases at a predetermined pressure within the tube envelope 10, it is possible to provide the desired tube characteristics. For example, it was desired to operate the tube of Fig. 1 with an operating voltage of 75 volts across the tube and a current flow of 1 milliampere. To provide a

cathode emitting surface having a sufficiently low work function as well as long life, misch metal is used to coat the upper surface of the cathode electrode 14. A gas mixture of around 99% neon and 1% argon is maintained at around 37 millimeters within the tube. These conditions of gas mixture and pressure as well as cathode surface will provide approximately a 75 volt drop across the tube and a normal cathode current density of 1 milliampere per square centimeter of cathode surface area. It is not necessary to be limited to misch metal for determining the work function of the cathode 14 or to the percentages of gas mixture, or to the gas pressure listed above. Other materials such as barium or caesiated antimony, for example, having an appropriate work function may be substituted for the misch metal coating on the cathode surface 14. Also, other mixtures of other gases may be used at corresponding pressures to provide similar operating characteristics of the tube of Fig. 1. The effects of varying the conditions and materials in tubes of this type are well known to those skilled in the art.

Fig. 2 discloses a well known relationship between the current and voltage of a glow discharge tube of the type described for Fig. 1. If the current is maintained sufficiently low by means of an external resistance, the discharge covers only a portion of the cathode surface 14. An increase in the current through the tube causes the discharge to spread over a greater portion of the cathode surface so that the current discharge per unit area or the current density of the tube discharge as well as the voltage drop across the tube will remain constant during this period of current increase. This condition is shown in Fig. 2 by the curved portion between the points A and B. This portion of the curve illustrates a condition of a constant normal current density. The curve between A and B is characteristic of glow discharge tubes and this range of operation is conventionally utilized in voltage regulator circuits where it is necessary to maintain a constant D. C. output voltage across a load. However, it is well known that one of the most serious difficulties in the use of glow discharge tubes operated within these limits is the rapid shifting or the abrupt small changes in voltage across the tube during tube operation. These jumps are not accumulative but merely are changes back and forth in the order of tenths of volts from the average tube voltage. Under some conditions, these abrupt changes of the tube voltage can be ignored. However, under other conditions, such rapid shifts in the voltage of the tube cannot be tolerated. It has been necessary then to design a glow discharge tube in which these rapid shifts in tube voltage are eliminated.

The principal cause for the rapid changes in tube voltages described above is the jumping of the glow discharge from one portion of the cathode surface to another unused portion of the surface, having a different work function. It is well known in tubes of this type that with the current density remaining constant, the total tube current may be increased until the glow discharge covers the entire surface of the cathode electrode. At this point the tube has reached the critical condition at which it is no longer possible to increase the current flow through the tube without a corresponding increase in the tube voltage and in the current density of the cathode discharge. This critical point is represented by B in Fig. 2 and the curve from B to C indicates the charac-

teristic rise in tube voltage as the current flow through the tube is increased.

I have designed the tube in Fig. 1 to be operated on that portion of the curve between points B and C. The current density discharge from the cathode surface changes beyond the critical point B and in relation to a change in the tube voltage. This portion of the curve between B and C is known as that of abnormal current density. I have found, that when a glow discharge tube is operated at a point in the abnormal portion B-C of the curve, the rapid changes in tube voltage as described above are eliminated. When operating in this abnormal range the glow discharge or cathode emission takes place from the entire cathode surface 14 and there is no unused portion of the cathode surface to which the "cathode glow" or discharge may shift. To maintain the cathode emission surface at a constant area, I have coated the under surface of the electrode plate 14 with an aluminum coating. This aluminum coating prevents the discharge glow from spreading to the under surface and causing variations in the tube voltage.

In operating a tube similar to that of Fig. 1, it may be connected in series with a resistance between the terminals of a source of regulated D. C. voltage. The resistance may be adjusted to a value such that the current flow through the gas tube may be large enough to provide a cathode glow discharge over all of the upper surface area of the cathode electrode 14 covered by the misch metal and such that the cathode discharge has an abnormal current density. Under these conditions, the tube will be operating in the current density range represented by curve B-C of Fig. 2.

As mentioned above, the work function of misch metal is such that the voltage drop across the tube is around 75 volts. The normal current density of a misch metal coated electrode at this voltage will be approximately 1 milliampere per cm. Since it is desired that the total current flow through the tube of Fig. 1 shall be approximately 1 milliampere, the cathode surface 14 is designed to have an area of 0.8 cm. This cathode surface area will result in the desired tube current of 1 milliampere when the tube is operated within the abnormal current density range.

Tubes, which have been constructed according to the above described manner, have given excellent results. These tubes after being properly processed and aged have been operated for test periods greater than 100 hours. By operating these tubes entirely within the abnormal current density range during these test periods, I have observed no abrupt changes in voltage greater than 0.05 volt. In operation, tubes of this type have proved of great value in voltage regulator circuits and for voltage reference applications.

In such applications a constant current flow which can vary only to the order of microamperes is maintained through the tube by a control circuit. When the tube is being operated within the abnormal current density range, such changes in the current in the order of microamperes will produce shifts in tube voltage in the order of millivolts and under extreme conditions these shifts in tube voltage may reach only 0.02 volt.

However, I have found, during the operation of tubes of the type described above and shown in Fig. 1, that although the abrupt shifts in tube voltage have been eliminated, another type of voltage instability has appeared. This voltage instability takes the form of a slowly increasing

voltage drop during the life of the tube. I have noted tubes of the above described type to have a voltage shift up to 2 volts and greater over a period of 200 hours of tube operation. This slowly shifting tube voltage is undesirable as it has to be continually adjusted for. Furthermore, under certain conditions the tube cannot be used due to this voltage change. It appears that the cause of such a change in the tube voltage is due to a changing cathode work function. This change in the cathode work function apparently is caused by a poisoning of the cathode emitting surface by deleterious gases within the tube which could not be removed prior to tube operation.

I have found that the glass surface of the tube envelope 10 takes on a negative charge due to some unexplained affinity of the envelope for the negative electrons produced by the tube discharge. As the glass envelope 10 becomes negatively charged it apparently draws to it positive gas ions produced during the tube operation. This results in a bombardment of the inner surface of the envelope walls by the positive ions and it appears that this bombardment actively releases occluded gases from the envelope walls. These occluded gases consist in a large part of oxygen which when released within the tube poisons the emitting surface of the cathode sufficiently to change its work function. This then is effective in causing the gradual increase in the voltage drop of the tube.

I have found, however, that if the walls of the tubular envelope 10 are coated with a metallic film 36 that this gradual shift in tube voltage is eliminated. The best metallic film is that of the same metal as that of the cathode emitting surface. In Fig. 1 the metallic film is a coating of misch metal identical with that covering the cathode surface 14. If other metals are used for the cathode emission surface, the same metal used for the metallic film 36 produces best results.

It is not entirely clear just how this metallic film prevents the change in tube voltage. However, a logical explanation may be that the metallic coating 36 on the inner surface of the glass walls prevents the liberation of gas from the glass surface by ion bombardment. Either the metal film 36 shields the glass wall effectively from the ion bombardment or the metal film may form a means for sealing the porous surface of the glass to prevent escaping of the gas during the conditions of tube operation. Also, another explanation of the function of the metal coating on the inner surface of the glass tube is that the misch metal used may react chemically with the occluded gases released by the ion bombardment. Since the emitting surface of the cathode electrode is also covered by misch metal, any deleterious gas within the glass surface of the tube which may effectively poison the cathode emitting surface by reacting therewith, must first come in contact with the misch metal film on the inner surface of the tube. Thus, the gas will react chemically with the misch metal coating instead of with the misch metal cathode emitting surface.

This metallic coating 36 on the inner surface of the glass discharge envelope 10 may be applied in any desirable manner. However, I have found it advantageous to deposit the metallic film 36 by evaporation. A lump of misch metal is fastened to the anode rod 20 in a position shown by dotted lines 38. During the aging of

the tube the anode rod is connected to the negative terminal of a source of voltage while the cathode plate 14 is connected to the positive terminal. With the establishment of an appropriate voltage between the negative rod 20 and the positive plate 14 the misch metal lump 38 is bombarded with positive ions causing it to be sputtered and to evaporate. This evaporation continues until all of the tubular wall surface below the mica disc 28 is covered with a metal film. Furthermore, the cathode plate 14 is covered with a uniform layer of the misch metal. The misch metal layer 36 on the tube surface is established sufficiently below the level of plate 14 so that the region of the glow discharge between the cathode 14 and anode 20 is completely enclosed by the metal coating 36. It has been found that the metal coating should completely cover all portions of the glass tube 10 which may be subjected to the positive ion bombardment. This extent of the metal coating from the mica 28 to a point below the cathode disc 14 has proved sufficient to eliminate the freeing of the occluded gases by positive ion bombardment.

The glow discharge tube described above which is designed according to my invention has eliminated two sources of trouble during tube operation, by solving the problem of rapid voltage shifts and also the problem of gradual tube voltage change. I have a gas discharge tube which has greater application than the conventional glow discharge tube. This improved tube may be depended upon to maintain a more constant voltage in applications where shifts of tube voltage in the order of tenths of volts have proved detrimental. Also, this tube which maintains a more constant voltage drop has found much valuable use as a voltage reference source in equipment where voltage changes found in conventional tubes prove detrimental.

While certain specific embodiments have been illustrated and described, it will be understood that various changes and modifications may be made therein without departing from the spirit and scope of the invention.

What I claim as new is:

1. A glow discharge device comprising an envelope, a gaseous medium within said envelope, an anode electrode and a cold cathode electrode enclosed within said envelope to provide a glow discharge therebetween, a substantial portion of the interior surface of said envelope being exposed to said glow discharge, a metal coating on said cathode electrode for determining its work function, said coating having inherent gettering properties, and a coating of the same metal on substantially the entire inside surface of said envelope exposed to said discharge to inhibit the liberation of gas from said surface.

2. A glow discharge device comprising an envelope, a gaseous medium within said envelope, an anode electrode and a cold cathode electrode enclosed within said envelope to provide a glow discharge therebetween, a substantial portion of the interior of said envelope being exposed to said discharge, a misch metal film deposited on a portion of the surface of said cathode electrode for determining the work function of said cathode electrode, a misch metal coating on substantially the entire inside surface of said envelope exposed to said discharge to inhibit the liberation of gas from said surface.

3. A glow discharge device comprising an envelope, a gaseous medium within said envelope, a rod-shaped anode electrode mounted within said

envelope, a flat cold cathode electrode within said envelope and spaced from said anode electrode to provide a glow discharge therebetween, a metal deposited on a portion of the surface of said cathode electrode for determining the work function of said cathode electrode, said metal having inherent gettering properties, and a metallic coating on the entire inside surface of said envelope exposed to said discharge to inhibit the liberation of gas from said surface, said metallic coating including the same metal deposited on said cathode portion.

4. A glow discharge device comprising an envelope having a tubular portion, a gaseous medium within said envelope, an annular disc shaped cold cathode electrode coaxially mounted within said tubular envelope portion, a misch metal coating on a portion of the surface of said cathode electrode for determining its work function, an anode electrode rod within said tubular envelope portion, said anode rod coaxially extending through the open center of said annular cathode electrode and spaced therefrom to provide a glow discharge therebetween, and a misch metal coating on substantially the entire inside surface of said envelope portion.

5. A glow discharge device comprising an envelope having a tubular portion, a gaseous medium within said envelope, a circular plate cathode electrode coaxially mounted within said tubular envelope portion, said circular cathode plate having an aperture at the center thereof, an anode electrode rod within said tubular envelope portion, said anode rod coaxially extending through the aperture of said cathode plate and spaced therefrom, a misch metal coating on one side of said cathode plate to determine the work function of said cathode electrode, an aluminum coating on the other side of said cathode plate to inhibit a discharge between said other side of the cathode plate and said anode electrode, and

6. A misch metal coating on the inside surface of said tubular envelope portion in the region of said discharge.

6. A glow discharge device comprising an envelope having a tubular portion, a gaseous medium within said envelope, a circular plate cathode electrode coaxially mounted within said tubular envelope portion, said circular cathode plate having an aperture at the center thereof, an anode electrode rod within said tubular envelope portion, said anode rod coaxially extending through the aperture of said cathode plate and spaced therefrom, a misch metal coating on one side of said cathode plate to determine the work function of said cathode electrode, an aluminum coating on the other side of said cathode plate to inhibit a discharge between said other side of the cathode plate and said anode electrode, and a coating of a chemically active metal on the inside surface of said tubular envelope portion in the region of said discharge.
